Primary Examiner — Joseph Kukella*Assistant Examiner* — Darryl J Dardenne(74) *Attorney, Agent, or Firm* — Alfred M. Walker(57) **CLAIM**

We claim the ornamental design for a clip-on universal bottle holder, as shown and described.

DESCRIPTION

FIG. 1 is a rear perspective view of the clip-on universal bottle holder.

FIG. 2 is a right side elevation view of the clip-on universal bottle holder, the left side elevation view being a mirror image thereof.

FIG. 3 is a top plan view thereof.

FIG. 4 is a front elevation view thereof; and,

FIG. 5 is a rear elevation view thereof.
